UNITED STATES PATENT OFFICE.

JAMES EDWARD WILLIAMS, OF ENTERPRISE, MISSISSIPPI.

PAPER-ROLL HOLDER.

Application filed October 8, 1924. Serial No. 742,393.

To all whom it may concern:

Be it known that I, JAMES EDWARD WILLIAMS, a citizen of the United States, residing at Enterprise, in the county of Clarke, 5 State of Mississippi, have invented a new and useful Paper-Roll Holder; and I do hereby declare the following to be a full, clear, and exact description of the invention, such as will enable others skilled in the art 10 to which it appertains to make and use the same.

The invention relates to paper roll holders, and has for its object to provide a device of this character comprising a shaft formed 15 from two sections detachably connected together and provided with cones thereby allowing the device to be easily and quickly placed within a roll of paper and obviating the loss of time and trouble now experienced 20 with devices of this character.

A further object is to provide the inner end of one of the shaft sections with a sleeve having internal thread, and in which sleeve the threaded end of the other shaft section 25 is received. Also to provide the sleeve with a flared opening for the reception of the convexus end of the other shaft section, thereby allowing the sections to be easily 30 guided into axial relation when placing the device on a roll of paper.

With the above and other objects in view the invention resides in the combination and arrangement of parts as hereinafter set forth, shown in the drawing, described and 35 claimed, it being understood that changes in the precise embodiment of the invention may be made within the scope of what is claimed without departing from the spirit of the invention.

40 In the drawing:—

Figure 1 is a vertical longitudinal sectional view through the paper roll holder.

Figure 2 is a side elevation of the inner end of the sleeve carrying shaft.

45 Figure 3 is a side elevation of the inner end of one of the shaft sections.

Figure 4 is a sectional view taken on line 4—4 of Figure 1.

Referring to the drawing the numeral 1 designates a conventional form of roll of 50 paper and 2 the cylindrical chamber which extends axially therethrough. Heretofore spindles of various constructions have been used for supporting rolls of papers, however these spindles have been made in one 55 piece and have been extremely difficult to place in position within the roll. To obviate this difficulty spindle 3 is provided, which spindle comprises axially alined shaft sections 4 and 5, the outer ends of which 60 are provided with reduced bearing members 7 adapted to be received in bearings of any suitable supporting brackets. Secured to the shaft sections 4 and 5 by means of screws 8 are cone members 9, which members are 65 adapted to be forced into the opposite ends of the chamber 2 of the roll of paper for securely holding and supporting the roll of paper. Secured to the inner end of the 70 shaft section 4 by means of screws 10 is a sleeve 11, the outer end 12 of which is flared, and which flared end allows the convexus end 13 of the shaft section 5 to be easily and accurately guided to axial position in relation to the shaft section 4 when the spindle is assembled. The inner end of the shaft section 5 is provided with thread 14, therefore it will be seen that after the shaft sections have been guided into axial alignment the sections may be secured together 80 by rotating either section, which action not only secures the sections together but jams the cones 9 into the ends of the roll of paper 1, thereby securely holding the roll of paper 85 on the spindle.

From the above it will be seen that a paper roll spindle is provided, which is formed from two sections, which may be easily and quickly connected together within the chamber of a roll of paper, and means is provided 90 whereby the sections may be connected and drawn together for jamming the cones into position. It will also be seen, by providing the flared end 12 on the sleeve 11, the convexus end of the shaft section 5 will be 95 guided to position whereupon rotation of

either shaft section, the shaft sections will be threaded together, all of which operation may be easily and quickly accomplished by the operator without loss of time incident to many attempts to place the shaft sections in axial alinement.

The invention having been set forth what is claimed as new and useful is:—

The combination with a paper roll spindle, said spindle comprising cones, axially alined shaft sections on which said cones are mounted, of a connection between the inner

adjacent ends of said shaft sections, said connection comprising a flared internally threaded sleeve carried by one of said shaft sections, a partition within said sleeve spaced from its ends and engaging the end of one of the shaft sections, the inner end of the other shaft section being threaded and convexed.

In testimony whereof I have signed my name to this specification.

JAMES EDWARD WILLIAMS.
